UNITED STATES PATENT OFFICE.

ARTHUR G. FITZNER, OF CHICAGO HEIGHTS, ILLINOIS.

SUBGRADE TEMPLATE.

Application filed September 12, 1925. Serial No. 55,950.

In the construction of concrete pavements, one of the requirements is that the sub-grade, before being covered with concrete, must have a predetermined elevation and contour at all points in the area upon which concrete is to be deposited.

This invention therefore relates to an improved steel sub-grade template of considerable weight and strength adapted to be propelled by the concrete mixer and carrying a row of leveling teeth on the advance side and reenforced removable template plates on the rear side so that as the sub-grade template is advanced by means of rollers supported on side forms substantially every portion of the sub-grade is tested and all high spots are encountered by the scraping teeth which loosen the earth, permitting the template proper to level the sub-grade to its proper elevation and contour.

It is an object of this invention to provide a template for concrete road construction work, said template being constructed of steel and being of a weight sufficient to permit scraping teeth to cut down and furthermore permitting the template proper to reduce the sub-grade surface to its proper elevation and contour.

It is also an object of this invention to provide a sub-grade template constructed of steel adapted to be dragged along after a concrete mixer to cause the sub-grade to be properly scraped and leveled to its required elevation and contour preparatory to having concrete from said mixer deposited thereon to a prescribed depth to meet stated requirements.

It is further an object of this invention to provide a steel sub-grade template wherein the ends are provided with rollers to support the same on side forms and also having rollers engaged on the inner sides of said forms to hold the template against lateral shifting as it is advanced by means of a mixer to cut and level the sub-grade to its proper elevation and contour.

It is furthermore an object of this invention to provide a sub-grade template of steel construction to span a road and carrying adjustable teeth on its advance side and removable template plate sections on the rear side.

It is an important object of this invention to provide an improved sub-grade template of heavy steel construction having adjustable cutting teeth on one side and reenforced

removable template plate sections arranged on the other side so that as the template is advanced by attaching the same to a concrete mixer the teeth will scrape and loosen high spots to permit the template plate sections to properly level the sub-grade to its proper elevation and contour prior to the covering of the sub-grade to a predetermined thickness with concrete delivered from the mixer which propels the sub-grade template.

Other and further important objects of this invention will be apparent from the disclosures in the drawings and specification.

The invention (in a preferred form) is illustrated in the drawings and hereinafter more fully described.

On the drawings:

Figure 1 is a plan view of a road under construction showing the side forms and a concrete mixer having connected thereto an improved sub-grade template embodying the principles of this invention.

Figure 2 is an enlarged fragmentary plan view of one end of the sub-grade template with parts broken away and parts omitted.

Figure 3 is a front elevation of one end of the sub-grade template showing parts in section.

Figure 4 is a rear elevation on a reduced scale of the entire sub-grade template.

Figure 5 is a detailed transverse section taken on line V—V of Figure 2.

As shown on the drawings:

The reference numeral 1 indicates a properly constructed road sub-grade of proper elevation and contour having a portion thereof covered with concrete 2 poured and leveled to proper thickness to meet road requirements. The reference numeral 3 indicates that portion of the road bed which has not yet been properly graded by the sub-grade template. Removably mounted longitudinally along each side of the road bed are concrete rails or forms 4 properly anchored in position to determine the proper width of the road and further serving as a track upon which horizontal supporting rollers 5 are adapted to run to hold the improved sub-grade template supported in its proper position transversely of the road. The horizontal rollers are supported on stub shafts 6 which are vertically movable in slotted bracket plates 7 carrying set screws 8 permitting the rollers to be raised or lowered with respect to said brackets as desired. Secured to the angle brackets 7 are connect-

ing plates or bars 9 which rigidly support a horizontally positioned steel I-beam 10 in position between the pair of roller carrying brackets 7 which form the end members of 5 the sub-grade template.

Rotatably mounted on the bottom side of each of the brackets 7 is a pair of vertical rollers 11 which is adapted to track on the inner faces of the side forms 4 for the purpose of holding the sub-grade template in proper position against lateral shifting with respect to the road bed. The vertical rollers also act to prevent the template from riding off of the forms. The main I-beam 10 is positioned with the web thereof in a horizontal position so that the flanges of the supporting beam are vertically disposed with the advance flange of the I-beam having a plurality of steel scraping bars or teeth 12 rigidly secured thereon in spaced relation by means of clamps 13 or other suitable means. The teeth 12 are adjustably mounted in position with the lower cutting edges thereof in a line conforming to the contour of the 25 sub-grade which is to be produced. It will thus be seen that the teeth 12 are clamped in a position set at sub-grade elevation to scrape loose all material above sub-grade elevation preparatory to having said cut off material 30 leveled to proper elevation by the template proper.

The rear flange of the I-beam 10 has rigidly bolted thereto a plurality of template plate sections 14, the lower edges of which 35 are cut to conform to the contour of the sub-grade. The template plate sections 14 are reenforced by means of braces 15. Rigidly but removably bolted to the bottom edge of each of the template plate sections 14 is an 40 angle iron protecting shoe 16 to protect the template edges of said template plate sections.

It will thus be noted that the protecting template shoes may be readily replaced when 45 worn at a comparatively small cost. The template shoes thus act as guards for the lower edge of the template proper and thereby insure the accuracy of the template at all times. It will also be noted that the 50 template plate sections being removably bolted in position permit the same to be removed or changed so that different shapes of sub-grades may be readily obtained.

The improved steel sub-grade template is 55 adapted to be positioned across the road as shown in Figure 1 with the supporting rollers 5 running on the forms 4. The sub-grade template is adapted to be pulled along by the concrete mixer 17 having caterpillar 60 treads 18 and a framework 19. The mixer bucket 20 is supported on a bucket boom 21 which projects rearwardly and may be swung transversely of the finished sub-grade 65 section 1 to permit the concrete to be poured in the positions where it is needed. The

mixer 17 is also provided with an overflow pan 22 to prevent concrete from dropping in front of the sub-grade template to clog up the template teeth. It will of course be understood that any desired type of concrete 70 mixer may be used for mixing the concrete and for propelling the sub-grade template along the road. Connected to the concrete mixer frame 19 are the ends of a pair of pull rods 23, the other ends of which are removably connected to the end portions of the template I-beam 10.

In case the sub-grade template has been advanced too far and it is desired to back the same up, a pair of cables or rods 24 are 80 secured to the web of the I-beam 10. Said rods 24 are provided with hooks 25 to permit the same to be hooked to the bucket 20 so that the sub-grade template may be moved backwardly as the bucket is advanced on the boom 21. When this is done it will of course be understood that the pull rods 23 are released from the sub-grade template I-beam 10. As shown in Figure 1, a guide rod or bar 26 is connected to the mixer frame 19 85 and extends transversely to one side of the road and is adapted to be advanced along the inner face of one of the forms 4 to serve as a guide for the purpose of steering the mixer along the crown or center of the sub-grade. The guide member 26 thus acts as a means whereby the mixer may be held to the crown or middle of the road thereby obviating any undue side pulls or strains on the sub-grade template. As clearly shown in Fig. 1 the 90 ends of the sub-grade template I-beam 10 are spaced a short distance from the inner faces of the forms 4 to permit the sub-grade template to clear or pass over overlapping reenforcing rods or bars which are positioned substantially parallel to the sides of the road adjacent the inner faces of the forms 4.

The operation is as follows:

In the construction of concrete pavements, 110 after the sub-grade has been prepared to what is believed to be substantially the correct elevation and contour, side forms 4 are mounted in position along the side of the road for the purpose of affording means for building the road to the required width and along a predetermined or selected path. After the initial preparation of the sub-grade, a concrete mixer is run onto the crown 115 of the sub-grade and the forward ends of the pull rods 23 are connected to the mixer framework 19 as shown in Figure 1. The rear ends of the pull rods 23 are removably clamped or engaged on the advance flange 120 of the sub-grade template I-beam 10 to permit the sub-grade template to be pulled or dragged behind the mixer as the mixer is advanced along the sub-grade. The improved 125 steel constructed sub-grade template is adapted to span the road and is supported 130

by means of the horizontal rollers 5 which track along the upper surfaces of the forms 4 which act as tracks along which the sub-grade template is adapted to be advanced.

5 To prevent the sub-grade template from running off of the forms 4 and also preventing lateral movement of the sub-grade template, the vertical rollers 11 are supported on the brackets 7 and track on the inner faces of the forms 4. The vertical rollers 11 are of thin construction to permit the same to pass above the marginal reenforcing rods for the concrete pavement which are placed adjacent the inner faces of the forms 4 for the purpose of reenforcing the outer margins of the concrete road when completed.

As the concrete mixer is advanced a predetermined distance along the sub-grade the area 1 (Figure 1) is prepared and tested ready to have concrete poured thereon. The area 1 is prepared by means of the improved steel constructed sub-grade template embodying the principles of this invention, said sub-grade template being of sufficient strength to prevent sagging and also adapted to ride over the sub-grade in close contact therewith so that as the sub-grade template is advanced the teeth 12 which are set to correspond to the contour of the template 14, act as a means for scraping any high spots in the sub-grade to loosen the material which projects above the required elevation at which the sub-grade is to be constructed. After the cutting down of the high spots in the sub-grade by means of the teeth 12, the angle iron shoes 16 of the template 14 ride over the scraped sub-grade to level the same to the required elevation and contour. The loosened material cut off by the teeth 12 is either used to fill in hollow places or may be held by the front of the template until a sufficient amount has been accumulated to warrant the removal of the same from the front of the sub-grade template. The weight of the steel sub-grade template is sufficiently great to hold the same in its proper position with the supporting rollers 5 resting on the forms 4 so that a highly accurate finished sub-grade is produced by means of the sub-grade template.

After the area 1 has been reduced to the required contour and elevation, the concrete mixer is set in operation to prepare the concrete and deposit the same in the bucket 20 which is then run out on the boom 21 and dumped to deposit the concrete in the area which is to be covered. The boom 21 may be swung into different positions so that within a very short time the required amount of concrete is poured to cover the area 1. Prior to the pouring of the concrete the side reenforcing rods and the center reenforcing bars may be placed in position so that the concrete is poured around the same. After

the concrete has been poured into the desired positions the concrete is leveled and finished by any desired means so that the thickness of the concrete over the entire sub-grade will conform to the standard depth requirements. As the concrete is poured over the finished sub-grade the mixer is advanced, thereby pulling the sub-grade template along the course of the road to permit the same to continue reducing the sub-grade to its proper contour.

In case it becomes necessary to move the sub-grade template rearwardly to permit the removal of loosened material from the front of the sub-grade template or for any other reason the pull rods 23 are released and the hooks 25 of the rods 24 are hooked to the bucket 20 which may be run outwardly on the boom 21 thereby causing the sub-grade template to be pulled back to the position desired.

As shown in Figure 1, an overflow pan 22 is carried by the concrete mixer frame 19 below the loading position of the bucket so that any concrete which is spilled will be deposited in the overflow pan and will not drop in front of the sub-grade template to clog the teeth 12.

When the sub-grade template is first put in position on the job it is of course necessary to position the sub-grade template so that it will cut off the grade at the proper elevation. In order to permit this adjustment of the sub-grade template the stub shafts 6 carrying the supporting rollers 5 are adjusted in the slotted bracket members 7 by means of the set screws 8. The rollers 5 may thus be set so that the sub-grade template will be properly positioned across the road to permit proper grading to the required elevation and contour.

The teeth 12 which are held in position by means of the clamps 13 may be removed individually when necessary so that an arrangement is afforded whereby the teeth 12 may be replaced when worn or broken, or adjusted if necessary. The template proper is constructed of a plurality of template sections each having a removable angle iron shoe so that any of the template sections or the shoes thereon may be removed when worn at a substantially small cost and thus preserve the accuracy of the template at all times. It will be seen that by constructing the template proper of a plurality of plate sections the expense of recutting a new template edge is obviated. It will also be noted that with this construction the template sections may be changed for different shapes of sub-grade and the teeth 12 may be adjusted to conform to the corrected or changed contour of the template proper.

The improved sub-grade template is of sturdy construction and of sufficient weight to produce an accurate sub-grade for a con-

crete pavement in a substantially short time and at a reduced cost. The improved sub-grade template is adapted to test substantially every point in the grade so that the required depth of the concrete may be obtained without any difficulty thereby producing a finished concrete pavement which will stand up to specifications and pass all tests to which the same is subjected.

I am aware that numerous details of construction may be varied through a wide range without departing from the principles of this invention, and I therefore do not purpose limiting the patent granted hereon otherwise than necessitated by the prior art.

I claim as my invention:

1. A sub-grade template comprising a beam, roller supports adjustable on the ends thereof adapted to track over forms on the side of the road to hold the beams supported in position, guide rollers for guiding the sub-grade template along said forms and over the grade, a plurality of teeth adjustably carried directly on the advanced side of the beam, and a template carried on the rear side of the beam, said teeth being set to conform to the contour of said template.

2. A sub-grade template comprising a beam, brackets connected to the ends thereof, supporting rollers adjustably mounted on the brackets and adapted to track on forms on the side of a road under construction, guide rollers on said brackets adapted to track on the inner surface of said forms to guide the course of the sub-grade template over the grade, a plurality of teeth positioned at spaced intervals across the advance side of the beam, clamping means for holding said teeth removably secured in position on the advance side of said beam, a plurality of template sections removably secured on the rear side of said beam, and shoes removably secured on the template edges of said sections to reenforce and protect the same.

3. A sub-grade template comprising a steel beam adapted to be positioned transversely of a road under construction, roller means at the ends of said beam for supporting the same, teeth secured to one of the flanges of said beam for the purpose of permitting high spots in the sub-grade to be cut down, and a template on another flange of said beam adapted to permit the sub-grade

to be reduced to its required contour and elevation.

4. A sub-grade template comprising a steel beam, roller means on the ends thereof for supporting the same, guide rollers carried by said roller means, a plurality of steel teeth positioned in spaced relation across one side of the beam, clamps for removably holding the same secured in position, a plurality of template sections removably secured to the opposite side of said beam, braces for reenforcing the same, and shoes on the lower cutting edges of said sections to reinforce and protect the same.

5. A sub-grade template comprising a beam adapted to be positioned transversely of a road under construction, adjustable means for supporting the same on the forms on the side of the road, a template on one side of said beam, and a plurality of cutter teeth transversely adjustable on the opposite side of said beam, said cutter teeth being arranged so that the cutting edges thereof will form a contour corresponding to the contour of the template.

6. A sub-grade template, comprising a steel beam, brackets secured to the ends thereof, guide rollers on said brackets adapted to track on the inner sides of forms at the side of the road, supporting rollers, means for adjustably supporting the same on said brackets to permit adjustment of the sub-grade template with respect to the grade of the road, a template on one side of said beam, and cutting means adjustably mounted on the opposite side of said beam.

7. A sub-grade template comprising a steel I-beam, brackets on the ends thereof, supporting rollers and guide rollers on said brackets, a template on one flange of said I-beam, shoes carried by said template, and cutter members on the opposite flange of said beam arranged to conform to the contour of the shoes on said template.

8. A sub-grade template comprising a steel I-beam, adjustable means for supporting the same on the forms at the side of a road under construction, scraper means removably secured to one flange of said I-beam, a plurality of template sections secured to the other flange of said I-beam, and template shoes removably secured to said template sections.

In testimony whereof I have hereunto subscribed my name.

ARTHUR G. FITZNER.
